UNITED STATES PATENT OFFICE.

GERHARDT E. GRIMM, OF PHILADELPHIA, PENNSYLVANIA.

GUARD FOR THE MOUTHPIECES OF TELEPHONE-TRANSMITTERS.

No. 828,494.

Specification of Letters Patent.

Patented June 12, 1906.

Original application filed August 12, 1905, Serial No. 273,879. Divided and this application filed May 18, 1906. Serial No. 317,419.

To all whom it may concern:

Be it known that I, GERHARDT E. GRIMM, a citizen of the United States, residing at Philadelphia, in the county of Philadelphia and State of Pennsylvania, have invented new and useful Improvements in Guards for the Mouthpieces of Telephone-Transmitters, of which the following is a specification.

My invention relates to new and useful improvements in guards for the mouthpiece of telephone-transmitters, and especially to guards which are adapted to be detachably engaged with the transmitter and include in this structure an antiseptically-treated film or diaphragm which when the guard is in operative position is disposed over the entrance to the transmitter to prevent the accumulation of disease germs in the mouthpiece to the transmitter, as well as to destroy such germs, so as to prevent the possible spread of disease.

The primary object of the invention is to provide a guard of the character mentioned which is simple in construction, inexpensive of production, and which will effectively attain the purposes for which it is devised.

A further object is to provide a new and improved means for detachably supporting the guard in operative position upon the transmitter.

The invention, broadly and generally stated, consists in a guard embodying in its structure an apertured device having improved and simplified means to engage the transmitter-mouthpiece to maintain the guard in operative position, the aperture in said guard being closed by a sheet or film of antiseptically-treated material.

I have fully and clearly illustrated my invention in the accompanying drawings, to be taken as a part of the invention, and wherein—

Figure 1 is a perspective view of a structure embodying the invention and shown attached in operative position to a telephone-transmitter. Fig. 2 is a transverse central section thereof. Fig. 3 is a view in rear elevation. Fig. 4 is a view in rear elevation of another form of the invention. Fig. 5 is a central transverse section through the form shown in Fig. 4; and Fig. 6 is a view of another form in transverse central section, showing the same applied to the mouthpiece of a transmitter.

Referring to the drawings, the reference-numeral 1 designates a plate of any suitable

material, preferably cardboard or similar material, having the proper degree of rigidity, said plate being constructed to be supported across the mouthpiece 2 of the well-known form of telephone-transmitter and being formed with a central opening 3, which registers with the opening in the transmitter-mouthpiece when said plate is in operative position thereon.

The plate 1, as shown in the drawings, is preferably rectangular and is provided with suitable means for detachably engaging the mouthpiece 2 of the transmitter to support the plate in position for use. This engaging or attaching means consists of oppositely-disposed arms or wings 4 5, which may be formed integral with said plate 1, said wings or arms 4 5 being bent or folded rearwardly on the rear face of said plate with their unattached ends free and extending toward each other, as shown. In placing the complete guard in position on the mouthpiece 2 of the transmitter, as hereinafter described, the arms 4 5 are arranged to engage and grasp the said mouthpiece and serve to frictionally engage the latter at diametrically opposite points thereon. In order to provide for the more secure and effective engagement of the wings with the transmitter, the vertical free edge of each wing is formed with a curved recess 6, in which the mouthpiece is received and which curved portions embrace the circular mouthpiece 2 and afford a more satisfactory engagement than were said vertical engaging faces left straight.

Arranged over the front face of the plate 1 and in a substantially parallel plane thereto is a plate 7, having an opening 8 therethrough so located as to register with the opening 3 in the first-named plate, said plate 7 being preferably of the same size and contour as the plate 1. The two plates 1 and 7 are permanently secured to each other, so as to provide a practically integral structure, said plates being so secured on their vertical side edges as to have their inner faces in substantial surface contact. The means for securing the plates together consist of wire-staple fasteners 9 of well-known form, one of which is located at each corner of said plates, and closely adjacent the vertical edges thereof, the prongs of said staples being inserted through the plates 1 and 7 and the wings 4 and 5, so that not only are the said plates firmly secured together, but the wings 4 5 being secured or anchored to the plate 1 at a

point removed from their edges great rigidity and grasping strength is given to said wings, so that they form elastic or spring mouthpiece-engaging clips and hold the guard more effectually in position than if they were free to move on the fold by which they are connected to the plate 1. While I have shown the plates secured by wire staples as affording a simple and efficient means for this purpose, it is, however, obvious that other means might be employed, if desired, without departing from the spirit of my invention.

It will be seen that although the rear and front plates 1 and 7 are securely fastened together a space is afforded between them through which a film 13 of antiseptically-treated material may be inserted to take position between said disks or plates to cover the openings 3 and 8 therein in order to intercept the passage of the breath of the operator when the transmitter is in use and also to prevent access of dust and other foreign substance to the mouthpiece.

25 In Fig. 3 I have shown the disk 13 as being formed with a large number of minute perforations, which provide for the easy passage of the sound-waves into the transmitter, but do not affect or change the antiseptic and germ-destroying properties of the invention. It will be understood that while these perforations will permit the passage of sound-waves into the transmitter they are so minute that dust and other fine particles cannot pass therethrough.

30 I have shown a slightly-modified form of the invention in Figs. 4 and 5, in which the front plate 7 is formed with end folds 14, which are turned back upon the wings 4 and 5, said folds being also engaged by the fastening devices 9. This form is advantageous as providing a more finished and slightly article than that shown in Figs. 1, 2, and 3.

35 In that form of the invention shown in Fig. 6 the attaching wings or arms 4 and 5 are formed integral with the plate 7, the inner plate being dispensed with, and the diaphragm of antiseptically-treated material is secured upon the rear side of the said plate 7 by 40 a suitable adhesive. If desired, the side edges of the diaphragm may project far enough between the plate 7 and the arms 4 and 5 to be engaged by the fasteners 9; but this is not necessary, as the adhesive will efficiently 45 maintain the diaphragm in proper position over the opening 8. However, if the adhesive is not employed the fasteners will hold the diaphragm in position. This last-described form of the invention is especially desirable where a guard of very simple construction and small cost of production is required. Having thus described my invention, what I claim as new, and desire to secure by Letters Patent, is—

50 1. In a guard of the character described, a

plate having an opening, a film of antiseptically-treated material located over said opening and fastening-wings carried by said plate and adapted to engage the mouthpiece of a transmitter, said wings being recessed at 75 their free ends to conform substantially to the contour of and embrace the mouthpiece.

2. In a guard of the character described, a plate having an opening, a film of antiseptically-treated material located over said opening, fastening-wings formed integral with said plate and adapted to engage the mouthpiece of a transmitter, said wings being recessed at 75 their free ends to conform substantially to the contour of and embrace the mouthpiece, and 80 means to connect said wings to the plate at a point adjacent their bases.

3. In a guard of the character described, a plate having an opening, a film of antiseptically-treated material located over said opening, and oppositely-disposed fastening-wings formed integral with said plate and adapted to engage the mouthpiece of a transmitter, said wings being recessed at 85 their free ends to conform substantially to the contour of and embrace the mouthpiece, and 90 means to connect said wings to the plate at a point adjacent their bases.

4. In a guard of the character described, a plate having an opening, a film of antiseptically-treated material located over said opening, two of the sides of said plate being parallel to each other and each formed with an integral recessed fastening-wing folded onto the rear side of the plate and having their engaging portions directed toward each other, 95 and means to maintain said wings in folded and resilient condition.

5. In a guard of the character described, a plate having an opening, a film of antiseptically-treated material located over said opening on the front of said plate, oppositely-disposed recessed fastening-wings formed integral with said plate and folded onto the rear side of said plate and having their engaging portions directed toward each other, a second 105 apertured plate arranged over said film and first-named plate, and means for securing said plates together, said means also operating to maintain said wings in folded and 110 resilient condition.

6. In a guard of the character described, a plate having an opening, a film of antiseptically-treated material located over said opening, on the front of said plate, oppositely-disposed fastening-wings formed integral with 115 said plate and folded onto the rear side of said plate, and having their engaging portions directed toward each other, a second apertured plate arranged over said film and first-named plate, and means whereby the plates are secured together and the wings held in folded and resilient condition.

7. A guard for telephone - mouthpieces, comprising a plate having a film-covered sound-receiving aperture, holding-wings on 120

opposite sides of said aperture, and fastening means passing through said plate and wings at points within their marginal edges to secure said wings and plate together and form

5 resilient mouthpiece-engaging clips.
8. A guard for telephone-mouthpieces, comprising a plate having a film-covered sound-receiving aperture, infolded integral holding-wings at the edges of said plate, and
10 means for securing said infolded wings to said

plate at points within their marginal edges to afford resilient mouthpiece-engaging clips.

In testimony whereof I have hereunto set my hand in presence of two subscribing witnesses.
